UNITED STATES PATENT OFFICE.

GEORGE P. KINGSBURY, OF HOLLIS, NEW YORK, ASSIGNEE TO MERGENTHALER LINOTYPE COMPANY, A CORPORATION OF NEW YORK.

TYPOGRAPHICAL MACHINE.

Application filed June 22, 1927. Serial No. 200,521.

This invention relates to typographical machines, such as linotype machines of the general organization represented in Letters Patent of the United States, No. 436,532, to 5 O. Mergenthaler, wherein circulating matrices are released from a magazine in the order in which their characters are to appear in print and then assembled in line, the composed line transferred to the face of 10 a mold, the mold filled with molten metal to form a slug or linotype against the matrices which produce the type characters thereon, and the matrices thereafter elevated and returned through distributing mechanism 15 to the magazine from which they started. More particularly, it relates to machines of the above class equipped with a plurality of main magazines and a plurality of auxiliary magazines arranged in tandem 20 and movably mounted in the machine frame so that any pair selected respectively from the two sets may be brought into operative position for simultaneous use. In commercial machines of this type, the shifting 25 of the main and auxiliary magazines is ordinarily accomplished by separate hand levers located at the front of the machine; and, while this arrangement is thoroughly practical, the operation has always been 30 slow and tedious and more or less laborious.

The present invention is intended to do away with the prior hand shifting practice and contemplates a power-actuated mechanism, controllable by a single knob or handle 35 conveniently located at the front of the machine, whereby any selected magazine of one series or the other may be moved into operative position, as desired. While the invention is applicable to other types of multiple 40 magazine machines, in the preferred embodiment herein illustrated, the magazines of the two sets are mounted in separate or independent shift frames hinged respectively at their upper ends adjacent the distributors 45 and movable to bring any selected pair of magazines into operative relation to the assembling devices without disturbing the connection of the magazines with the distributors.

50 In the accompanying drawings, the invention has been shown merely in preferred form and by way of example, and obviously many changes and variations may be made therein and in its mode of adaptation which 55 will still be comprised within its spirit. It

is to be understood, therefore, that the invention is not limited to any specific form or embodiment except in so far as such limitations are specified in the claims.

Referring to the drawings:

Fig. 1 is a side elevation of a linotype machine, equipped with the present improvements, showing the lower magazine in operative position;

Fig. 2 is a similar view, on an enlarged scale, partly in section and partly broken away, showing the upper magazine in operative position;

Fig. 3 is a front elevation of the parts shown in Fig. 2, with the intermediate bracket and assembler entrance removed;

Fig. 4 is a transverse section taken on line 4-4 of Fig. 2;

Fig. 5 is a detail sectional plan view of the power-actuated mechanism for raising 75 and lowering the magazines;

Fig. 6 is a detail face view of the clutch which drives the crank arm for the auxiliary magazines; and

Fig. 7 is a similar view showing the clutch 80 which drives the crank arm for the main magazines.

The matrices of the regular fonts are stored in the superposed main magazines A, only two of which are herein shown but of 85 which a greater number might be employed, if desired. These magazines are supported upon the customary base frames A¹ hinged at their upper ends, as at A², and conjointly constituting a shift frame which is arranged 90 to be swung upwardly and downwardly in the machine to locate either of the magazines in operative relation to the fixed assembler throat or raceway B. Arranged at the side of the magazines A is a series of auxiliary, 95 or supplemental, magazines C supported in a shift frame made up (like that for the main magazines) of separate base frames hinged on axes (not shown) aligned with those of the base frames A¹.

The swinging of the respective shift frames to effect the interchange of the magazines supported thereby may be accomplished in any desired manner, the means herein employed being similar to those presented in the Kennedy Patent No. 1,386,786, 105 and consisting essentially of a toggle system which, when straightened out or extended, raises the shift frame to place the lower magazine in operative position, and when 110

collapsed, allows the shift frame to swing downwardly to bring the upper magazine in operative position. In the latter position (Fig. 2), the shift frame for the series of 5 main magazines banks upon a pair of set screws A^3 which are carried by the parallel side arms of a fixed U-shaped bracket O and which are adjusted so as to locate the upper magazine in registration with the assembler 10 throat B . In its raised position (Fig. 1), the shift frame is supported directly by the associated toggle system whose design is such that, when extended, the lower magazine will be properly located in operative 15 relation to the throat B . The said toggle system comprises two pairs of links D , D^1 intermediately connected by a transverse rod D^2 to which the lower members D^1 are fastened and on which the upper members 20 D are loosely mounted. At their lower ends, the members D^1 are pivoted by pins or screws D^3 to the side arms of the bracket O , and the members D are formed at their upper ends with open bearings or forks d 25 wherein engage pins a projecting laterally from lugs A^4 depending from the lower base frame A^1 . The rod D^2 is guided in curved slots O^2 of the bracket arms and is movable to and fro therein to effect the extension or 30 collapse of the toggle members D , D^1 . The movements of the rod D^2 are limited by the slots O^2 , the front walls of which are so arranged that the rod, as it is rocked forwardly, will be allowed to pass dead center 35 before it is stopped and, in this way, lock the magazines in their raised position.

The toggle system for the auxiliary magazines C (see Fig. 3) corresponds in structure and mode of operation to the one just described but, for the sake of clearness, the parts will be designated by different reference characters. Thus, the upper members E of the toggle links are connected at their upper ends with lugs C^1 depending from the 40 auxiliary shift frame and, at their lower ends, are loosely mounted on a transverse connecting rod E^2 , the latter being supported by the lower link members E^1 which are pivotally secured to the upright side members of a supplemental supporting frame O^3 . This frame, like the frame O , is slotted to 45 permit free movement of the rod E^2 in collapsing and extending the toggle system E , E^1 , to raise and lower the magazines C in 50 the manner required.

So far as described, the parts are or may be the same as those embodied in the commercial Model 26 Linotype and in themselves constitute no part of this invention.

60 According to the present invention, the swinging of the magazines is accomplished by means of a power-actuated gear mechanism which is common to both series of magazines and is controlled by a clutch device operable by a knob or handle located

conveniently above the keyboard K . The proposed mechanism (see Figs. 2 and 5) includes a lay shaft F journaled in a suitable bearing bracket F^1 and axially aligned with the customary fore and aft assembler drive 70 shaft G , the latter (see Fig. 2) being made hollow or tubular in form. At its rear end, the shaft F is provided with a worm F^2 , and at its forward end carries a bevel gear F^3 which, for reasons later to be pointed out, 75 is connected to the shaft by means of a friction or slip coupling F^4 . The shaft F receives its motion directly from a clutch member H^1 which is loosely mounted on the well known intermediate shaft H and is 80 capable of slight axial movement in both directions. A bevel gear H^2 (Fig. 5) is splined to the clutch member and arranged to mesh constantly with the bevel gear F^3 of the lay shaft F , the spline h permitting 85 the axial movement of the clutch member on the shaft H without disturbing the meshing of said gears. About midway of its length, the clutch member H^1 is formed with an annular groove h^2 and, at its opposite ends, 90 with jaw clutch portions h^3 and h^4 , the clutch portion h^3 being adapted to engage a cooperating clutch member h^5 keyed to the intermediate shaft H , and the clutch portion h^4 being adapted to engage a cooperating 95 clutch member h^6 loosely mounted on said intermediate shaft. The clutch members h^5 , h^6 are secured respectively to a pair of reversing bevel gears H^3 , H^4 , both of which 100 mesh with a bevel gear G^1 keyed to the fore and aft assembler drive shaft G . These three gears H^3 , H^4 and G^1 , rotate constantly, the gear H^3 being rotated in one direction directly by the intermediate shaft H , and the gear H^4 , which is loose on the shaft H , being 105 driven thereby through the gear G^1 in the opposite direction.

The operation of the clutch member H^1 is controlled by a small handle H^5 fastened to the front end of a straight connecting rod H^6 rotatably mounted in the hollow fore and aft assembler drive shaft G . A fork H^7 , pivoted by a connecting pin H^8 to a collar secured to the rear end of the rod H^6 , is arranged to engage the annular groove h^2 of the clutch member H^1 and is adapted to shift the latter into and out of engagement with the reversing gears H^3 , H^4 . Normally, the handle H^5 occupies the vertical position indicated and the clutch member H^1 stands 110 disengaged from both of said gears, the parts being maintained yieldingly in this neutral position by a detent H^8 (Fig. 2) which is mounted in the fork H^7 and engages a corresponding recess in the pivot pin H^8 . When 115 the handle H^5 is thrown to the right, the jaw portion h^4 of the clutch H^1 will be shifted into engagement with the clutch member h^6 of the gear H^4 and thereby establish a driving connection between the intermediate shaft 120 125 130

H and the lay shaft F which causes the latter to be rotated in a counter-clockwise direction. Conversely, when the handle is thrown to the left, the jaw portion h^3 of the clutch H^1 will be moved into engagement with the clutch member h^5 of the gear H^3 and, by the driving connection thus established cause the lay shaft to rotate in the opposite or clockwise direction.

Means operable by the lay shaft F are also provided for swinging both series of magazines about their respective pivotal axes, the swinging of the main magazines or the swinging of the adjacent series of auxiliary magazines being effected according to the direction in which said shaft is rotated. Such means (as best shown in Figs 2 and 4) comprise a stub shaft J journaled in an upright strut O⁴ of the machine frame and arranged at right angles to the lay shaft F below the rear end thereof. The shaft J is provided with a loose sleeve J¹ and with a loose worm wheel J³, the latter being arranged in mesh with the worm F², before mentioned. An ordinary ratchet clutch device J⁴, keyed to the shaft J and mounted in a recess j formed in one side of the worm wheel J³, is employed to effect a driving connection between the wheel and the shaft when the former is rotated in one direction; and a similar clutch device J⁵, arranged in a corresponding recess j¹ formed in the other side of the worm wheel and keyed to the inner end of the sleeve J¹, is employed to connect the wheel with the sleeve when the former is rotated in the other direction. As a result of this arrangement, when the worm wheel is turned in a clockwise direction according to Fig. 6, the sleeve J¹, through the medium of the clutch device J⁵, will be driven by the wheel independently of the shaft J; whereas the shaft, through the clutch device J⁴, will be driven independently of the sleeve when the wheel is turned in the reverse direction (see Fig. 7.) The shaft J has fast to it a crank arm J⁶ connected by a vertically disposed link J⁷ to the short arm of a pivoted bell crank lever J⁸. The sleeve J¹ likewise has fast to it a similar crank arm J² connected by a vertical link J⁹ to the short arm of a pivoted bell crank lever J¹⁰. The longer arms of these levers J⁸, J¹⁰ (see Fig. 3) are arranged in engagement with the respective toggle link connecting rods D², E² and, by the rotation of the crank arms J⁶, J², will swing the rods back and forth to raise and lower the magazines in the manner before described.

When it is desired to raise or lower the main magazines A to bring a selected font into operative position, it is merely necessary to throw the control handle H⁵ to the left. This operation shifts the clutch H¹ to the right into engagement with the reversing gear H³ and causes the lay shaft F, through the worm F², to turn the worm wheel J³ in

the direction indicated in Fig. 7. The balls of the clutch device J⁴ immediately become wedged between the concentric wall of the recess j and the inclined surfaces of the ratchet j² and thus rigidly connect the wheel J³ to the shaft J. If the magazines A happen to be in the upper position shown in Fig. 1, the short arm of the bell crank lever J⁸ will be drawn downwardly by the crank arm J⁶ and the link J⁷ as the shaft J begins to rotate, and the longer arm thereof rocked rearwardly to collapse the toggle links D, D¹. As the shift frame comes to rest on the set screws A³, the handle H⁵ is turned to its vertical or neutral position to disengage the clutch H¹ and thus break the driving connection. To bring the lower magazine into operative position, the operation is precisely the same, the handle being thrown to the left and the crank arm J⁶, by rotation of the shaft J, turned upwardly from its lower position (Fig. 2) to swing the upper arm of the bell crank lever J⁸ forwardly and thus straighten out the toggles. The size of the crank arm J⁶ in relation to the bell crank lever J⁸ will, of course, be determined by the throw required to collapse or expand the toggle links so that, when the shift frame banks on the set screws A³, the crank arm will have reached its lowermost position (Fig. 2) and, when the connecting rod D² has just passed dead center, the crank arm will have reached its uppermost position. The relation of the corresponding parts for raising and lowering the auxiliary magazines is the same. In this connection, however, it might be advisable to provide a little lost motion in the link J⁷, where it joins the bell crank lever J⁸, so as thus to prevent binding or breakage of the parts that might otherwise result, from slight inaccuracies in design or assembling, when the respective shift frames are swung to their upper or lower positions.

To bring one or another of the auxiliary magazines into operative position, the control handle is thrown to the right to engage the clutch H¹ with the reversing gear H⁴. The driving connection thus established between the intermediate shaft and the lay shaft F causes the worm wheel J³ to be turned in the opposite direction (see Fig. 6) and in this way renders the clutch device J⁵ effective, the latter being of the same type as the associated clutch device J⁴ but adapted to connect the wheel with the sleeve J¹, as previously stated. Rotation of the sleeve J¹ and the connected crank arm J² rocks the bell crank lever J¹⁰ through the connecting link J⁹ and, by the expanding and collapsing of the toggle links E, E¹, shifts the auxiliary shift frame respectively up and down to bring a selected magazine C into operative position.

Since a positive jaw or claw clutch H¹ is preferable to other types on account of its

delicate control, the friction slip coupling F⁴, hereinbefore mentioned, is incorporated in the proposed mechanism as a further precaution against damage to the magazines 5 or the fixed assembler throat B, that might be caused by a protruding matrix or similar interference.

Having thus described my invention, its construction and mode of operation, what I 10 claim and desire to secure by Letters Patent of the United States, is as follows:

1. In a linotype machine, a series of movable main magazines and a series of movable auxiliary magazines, in combination with 15 power-actuated means for bringing any selected magazine of either series into operative position, together with means for establishing an operative connection between said power-actuated means and either series 20 of magazines, or for rendering said means inactive upon both series simultaneously, as desired.

2. In a linotype machine, a series of movable main magazines and a series of movable auxiliary magazines, in combination with 25 power-actuated means common to both series for bringing any selected magazine of either series into operative position, together 30 with means for establishing an operative connection between said power-actuated means and either series of magazines, or for rendering said means inactive upon both series simultaneously, as desired.

3. In a linotype machine, a series of movable main magazines and a series of movable auxiliary magazines, in combination with 35 power-actuated gear mechanism, reversible at will, to bring a selected magazine of one series or the other into operative position, 40 together with means for establishing an operative connection between the main magazines and said gear mechanism when the latter is rotating in one direction and for establishing an operative connection between 45 the auxiliary magazines and said gear mechanism when the latter is rotating in the opposite direction.

4. In a linotype machine equipped with a series of movable main magazines and a series of 50 movable auxiliary magazines, the combination of the constantly driven intermediate shaft, a lay shaft operatively connected with both series of magazines, and intermediate reversible gear mechanism for 55 connecting the lay shaft with the intermediate shaft, whereby the magazines of one series or the other may be raised and lowered according to the direction of rotation of the lay shaft to bring a selected magazine into 60 operative position.

5. In a linotype machine equipped with a series of movable main magazines and a series of 65 movable auxiliary magazines, the combination of a shaft operatively connected to the main magazines, a sleeve mounted

thereon operatively connected to the auxiliary magazines, and common means for turning the shaft and sleeve respectively in opposite directions, whereby a selected magazine of one series or the other may be 70 brought into operative position.

6. In a linotype machine equipped with a series of movable main magazines and a series of movable auxiliary magazines, the combination of a shaft operatively connected 75 to the main magazines, a sleeve mounted thereon operatively connected to the auxiliary magazines, and power actuated means for turning the shaft and sleeve respectively in opposite directions whereby a selected 80 magazine of one series or the other may be brought into operative position.

7. In a linotype machine equipped with a series of movable main magazines and a series of movable auxiliary magazines, the combination of a lay shaft, reversible power driven gear mechanism for rotating the shaft in opposite directions, and means connected to the respective series of magazines and adapted by such opposite rotations of 85 the lay shaft to bring a selected magazine of one series or the other into operative position.

8. In a linotype machine equipped with a series of movable main magazines and a series of 90 movable auxiliary magazines, the combination of a worm wheel, mechanism for rotating the wheel in opposite directions, and means connected to the respective series of magazines and adapted by such opposite 95 rotations of the worm wheel to bring a selected magazine of one series or the other into operative position.

9. In a linotype machine, the combination 100 with a series of movable main magazines and a series of movable auxiliary magazines, said magazines being pivotally mounted so that a selected magazine of one series or the other may be brought into operative position, of means for swinging the magazines 105 including a crank shaft connected to the main magazines, a sleeve mounted thereon connected to the auxiliary magazines, and a power driven wheel adapted by its rotation in one direction to turn the shaft independently of the sleeve and by its rotation in the opposite direction to turn the sleeve independently of the crank shaft.

10. In a linotype machine, the combination 115 of a series of movable main magazines and a series of movable auxiliary magazines, a crank shaft connected to the main magazines and a sleeve mounted on said shaft connected to the auxiliary magazines, and means for rotating the shaft and sleeve to bring a selected magazine of the corresponding series into operative position including a worm wheel mounted on the shaft and power-actuated reversible gear mechanism 125 for turning the worm wheel, the latter being 130

adapted by its rotation in one direction to drive the crank shaft independently of the sleeve and by its rotation in the opposite direction to drive the sleeve independently of the crank shaft.

11. In a linotype machine, the combination of a series of movable main magazines and a series of movable auxiliary magazines, a crank shaft connected to the main magazines and a sleeve mounted on said shaft connected to the auxiliary magazines, and means for rotating the shaft and sleeve to bring a selected magazine of corresponding series into operative position including the transverse intermediate shaft, a hollow fore and aft assembler drive shaft geared thereto, a worm wheel mounted on the crank shaft, reversible gear mechanism driven by the intermediate shaft, a clutch for making or breaking a driving connection between the worm wheel and the reversing gears, and a control rod mounted in the hollow assembler shaft for operating the clutch, said worm wheel being adapted by its rotation in one direction to drive the crank shaft independently of the sleeve and by its rotation in the opposite direction to drive the sleeve independently of the crank shaft.

12. In a linotype machine, a series of pivoted main magazines and a series of pivoted auxiliary magazines, in combination with means for swinging the magazines about their respective axes to bring any selected ones into operative position, said means including a shaft provided with a crank arm connected to the main magazines, a sleeve journaled on said shaft and provided with a crank arm connected to the auxiliary magazines, a worm wheel mounted on the shaft, power driven means for rotating the wheel in opposite directions, a one-way clutch device adapted to establish a driving engagement between the wheel and shaft as the former is rotated in one direction, and a similar clutch device adapted to establish a driving engagement between the wheel and the sleeve as the wheel is rotated in the opposite direction.

13. In a linotype machine, the combination of a plurality of magazines movably mounted therein, a crank shaft connected to the magazines and adapted by its rotation to bring a selected one into operative position, and means for rotating the shaft including a worm wheel mounted thereon, a worm meshing with said wheel, and a power driven shaft for rotating the worm.

14. In a linotype machine, the combina-

tion of a plurality of magazines movably mounted therein, a crank shaft connected to the magazines and adapted by its rotation to bring a selected one into operative position, and power-actuated means for rotating the crank shaft including a worm wheel mounted thereon, the constantly driven intermediate shaft, a lay shaft having a worm meshing with said wheel, and an intermediate clutch for connecting and disconnecting the lay shaft with and from the intermediate shaft, as desired.

15. In a linotype machine, the combination of two series of magazines, and power-actuated means common to both series for rendering any selected magazine of either series operative, together with control means for causing said power actuated means to cooperate with either series of magazines to the exclusion of the other or render said means ineffective as to both series simultaneously as desired.

16. In a linotype machine, the combination of two series of magazines, and power-actuated gear mechanism, reversible at will, for rendering any selected magazine of either series operative, together with control means for causing said power actuated means to cooperate with either series of magazines to the exclusion of the other or render said means ineffective as to both series simultaneously as desired.

17. In a linotype machine, a series of movable main magazines and a series of movable auxiliary magazines, in combination with a common operating shaft therefor rotatable in opposite directions, means actuated by said shaft when rotated in one direction for moving the main magazines, and means actuated by said shaft when rotated in the opposite direction for moving the auxiliary magazines.

18. In a linotype machine, a series of movable main magazines and a series of movable auxiliary magazines, in combination with a common operating shaft therefor, power-actuated gear mechanism, reversible at will, for rotating said shaft in opposite directions, means controlled by said operating shaft when rotating in one direction for moving the main magazines, and means controlled by said operating shaft when rotating in the opposite direction for moving the auxiliary magazines.

In testimony whereof, I have affixed my signature hereto.

GEORGE P. KINGSBURY.
